UNITED STATES PATENT OFFICE.

HARRY A. DOUGLAS, OF BRONSON, MICHIGAN, ASSIGNOR TO DOUGLAS & RUDD MFG. CO.,
OF BRONSON, MICHIGAN, A CORPORATION OF MICHIGAN.

REFLECTING-LAMP.

1,261,788.

Specification of Letters Patent.

Patented Apr. 9, 1918.

Application filed February 18, 1917. Serial No. 149,670.

To all whom it may concern:

Be it known that I, HARRY A. DOUGLAS, citizen of the United States, residing at Bronson, in the county of Branch and State of Michigan, have invented a certain new and useful Improvement in Reflecting-Lamps, of which the following is a full, clear, concise, and exact description.

My invention relates primarily to reflecting lamps of the variety known as "spot lights" though features thereof are not to be restricted to such lamps and has a number of objects and advantages in view.

In accordance with one feature of my invention the reflector carrying casing and the handle are formed in separate pieces having interengaging formations that are forced into rigid engagement to make the handle and back element rigid with respect to each other. Where a bracket is employed it is held in place by the aforesaid interengaging formations of the handle and casing, being preferably interposed between such formations.

The bracket has a suitable universal connection; at its lower end, with a suitable anchorage and is held in relation with such anchorage by a pressure which is manually regulable.

My invention also contemplates the combination with a movably mounted lamp, of a mirror employed in conjunction with the lamp and having a mounting upon which it is moved that is distinct from the lamp mounting whereby this mirror may reflect objects to the rear of the automobile carrying the lamp without changing the angle of the lamp itself. In the preferred embodiment of the invention this mirror may also act as a pedestal upon which the lamp may be supported at various angles when the lamp is used as an inspection lamp.

I will explain my invention more fully by reference to the accompanying drawings showing the preferred embodiment thereof and in which Figure 1 is a side elevation, partially in section, of a reflecting lamp containing features of my invention; Fig. 2 is a longitudinal view, partially in section and partially in elevation, of portions of the structure illustrated in Fig. 1; Fig. 3 is a view on line 3-3 of Fig. 4; Fig. 4 is a view on line 4-4 of Fig. 1; and Fig. 5 is a view on line 5-5 of Fig. 4.

Like parts are indicated by similar char-

acters of reference throughout the different figures.

The concave reflecting part 1 of the structure may be the interior surface of a reflector containing casing 2, this surface being suitably polished or formed to have the desired capacity for reflection. The reflector carrying casing includes a rearwardly extending cylindrical tubular continuation 3 that constitutes a holder or mounting for the light source. A spring tongue 4 is integrally formed with a shell 5 that constitutes a holder for contact carriers, this spring tongue having ample clearance at its side margins to permit it freely to function. Some part of the tongue, such as the rear free end thereof, has a part 6 projecting therefrom which is narrower than the balance of the tongue and is slightly narrower than a slot 7 in the holder 3 whereby this portion may project into the slot while at the same time the side margins of the tongue 4 are adapted to press against the side margins of the slot 7. The tongue thus presses upon a surface of the holder 3 and, where there is but one tongue, forces the shell toward the opposite side of the holder whereby the shell is held in engagement with the holder 3. The slot 7 is elongated so that the shell 5 may be moved back and forth in its holder 3 whereby in the structure illustrated the position of the lamp bulb 8 which is carried by the forward end of the shell in front of the reflector may be adjusted with respect to the reflector. The base 9 of the lamp bulb 8 constitutes the forward contact carrier and as the arrangement illustrated is a double pole arrangement this contact carrier 9 carries two rear contacts 10 and 11. The lamp base or contact carrier 9 is provided with bayonet pins 12 engageable within bayonet seats 13 constituting parts of bayonet slots 14. The rear contact carrying plug 15 within the casing 2 is provided with terminal blocks 16 having binding screws 17 by which circuit wires may be secured to the terminal blocks. These terminal blocks are cylindrical and the forward ends thereof are tubular, springs 18 being included in the tubular portions of the terminal blocks and operating to press contacts 19, 20 forwardly into engagement with the contacts 10 and 11, all of these contacts being within the casing. The springs 18 and the contacts 19 and 20 thus not only

- 2
- serve to establish circuit for the lamp but also operate to hold the lamp base 9 in bayonet pin and slot connection with the shell 5.
- 5 The plug 15 is rotatable within the rear end of the shell 5 in order that it may perform its switching function and when thus movably mounted it is provided with bayonet pins 21 and which are receivable in alternate bayonet seats 22, 23, the plug being inserted from the front end of the shell with its pins passing along the bayonet slots 14 until they are in the zone that includes the bayonet seats 22, 23 whereafter the base of 10 the lamp bulb is inserted in the shell with its pins 12 placed in the bayonet seats 13. The springs 18 thus not only to serve to hold the bayonet pins 12 in the seats but also serve to hold the bayonet pins 21 in the seats 15 to which they are adjusted.
- It will be observed that the supplemental switching contacts 10 and 19 are eccentric with respect to the shell as are also the supplemental switching contacts 11 and 20 20 so that as the plug is turned these contacts are either brought into engagement or are separated according to the direction of movement of the switching plug 15. When the lamp is in open circuit the contacts 19 25 and 20 are pressed against the insulating portions of the lamp base that are adjacent the contacts 10 and 11; the springs 18 continuing to press the contacts 19 and 20 forwardly to maintain the bayonet pins upon 30 the switching plug and upon the lamp base in their respective bayonet seats. The shell and the parts within it are in front of the casing 2 and in order that the switching plug 15 may be turned or otherwise moved 35 with respect to the lamp base to cut the lamp in and out of circuit I employ a motion transmitting connection, in the form of a switching rod 24, which is connected at its inner end with the switching plug and 40 which is operable from the exterior of the casing. The outer end of this switching rod desirably has a gripping head piece 25 assembled therewith by means of a pin 26. This head piece may be gripped in order 45 that the rod 24 may be turned into on or off circuit positions and may be moved in and out to adjust the bulb.
- The switching mechanism which I have described is claimed in my co-pending application, Serial No. 149,666, filed February 55 19, 1917.
- The holder 3 is continued rearwardly and constitutes a part of the handle 27 by which the lamp may be manipulated, the 60 portion of the handle which is grasped being larger than the portion 3, which latter portion thus constitutes a neck portion. This arrangement affords suitable freedom 65 for the adjustment of the shell 5, there being ample clearance at the rear of the shell
- between it and the surrounding part of the gripping portion of the handle. The enlargement of the handle to the rear of the neck 3 thereof also affords suitable space in which the conductors 28 that lead to the 70 switching plug may be disposed and in which space the inner ends of the conductors may readily move when switching occurs.
- The portion 29 of the bracket 30 is interposed between the beads or flanges 31 of the handle. An annular space intervenes between these flanges or beads in which the rear of the reflector and the bracket portion 29 are received and the flanges are 75 firmly pressed into engagement with these parts whereby the handle, reflector and bracket are clamped into rigid relation. The lower end of the bracket 30 is in ball and socket connection with a split anchorage 80 32 between the split parts of which the lower end of the bracket is clamped by a clamping bolt 33. The clamp 32 is clamped to any suitable support, such as the wind shield 34, by clamping screws 35. By means 85 of this bolt 33 the clamp may be loosened to enable the lamp to be placed in any selected adjustment and may thereafter be tightened to maintain this adjustment.
- The frame 36 of the mirror 37 is, in the 90 embodiment of the invention illustrated, provided with trunnions 38 that are received in the branches of the bifurcated support 39. This support 39 is connected with some part of the lamp structure, being preferably a continuation of the bracket 30 that extends beyond the lamp supporting portion of the bracket from the place of connection of the bracket with the lamp structure. The mirror is back of the casing and 95 normally faces the rear so that it may reflect objects following the automobile carrying the lamp. It is not necessary, by means of the construction illustrated, to change the angle of the spot light in order to shift the 100 angle of the mirror since the mirror may readily be turned in its bearings without shifting the lamp. This characteristic is an advantage over prior constructions having rearwardly facing mirrors connected 105 with the lamps. The bearings in which the mirror is journaled are desirably stiff or of friction type so that when the lamp bracket is uncoupled the mirror may be 110 used as a base upon which the lamp may be 115 supported and with respect to which the position of the lamp may be changed as desired, for inspection. It will be observed that this mirror does not form a part of the casing, being supplied in addition thereto, so that its movement with respect to the casing nowise modifies the construction and function of the lamp itself.
- The conductors 28 are passed between the 120 side bars of the bracket 30 and find passage 125

at the rear of the neck 3 into the interior of the hollow handle.

The interiors of the reflector and handle are merged into one in which composite interior the light source is disposed and may be adjusted and in which the focusing and switching rod 24 may be moved and into which the head piece 25 may project to the extent required to secure the desired focal adjustment of the lamp, said switch being rotatable in any of its positions, to enable the switching of the lamp into and out of circuit. The rear face of the casing or at least the upper part thereof may be polished to constitute it a reflecting surface upon which objects at the rear may be reflected. As exhibited the lamp may readily be detached to be used as an inspection lamp.

20 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a reflecting lamp, the combination with a light transmitting cover; of a reflector carrying casing at the front of which said cover is disposed; a hollow handle; a bracket for supporting the lamp and which is clamped by the handle to the casing; a lamp bulb; and a shell carrying the lamp bulb and located in the part of the handle adjacent the casing.

2. In a reflecting lamp, the combination with a light transmitting cover; of a reflector carrying casing at the front of which said cover is disposed; a hollow handle formed separately from the casing; a bracket for supporting the lamp, the handle clamping the bracket and casing together; a lamp bulb; and a shell carrying the lamp bulb and located in the part of the handle adjacent the casing.

3. In a reflecting lamp, the combination with a light transmitting cover; of a reflector carrying casing at the front of which said cover is disposed; a hollow handle; a bracket for supporting the lamp and which is clamped by the handle to the casing; a lamp bulb; and a shell carrying the lamp bulb and mounted to move in and out and located in the part of the handle adjacent the casing.

4. In a reflecting lamp, the combination with a light transmitting cover; of a reflector carrying casing at the front of which

said cover is disposed; a hollow handle formed separately from the casing; a bracket for supporting the lamp, the handle clamping the bracket and casing together; a lamp bulb; and a shell carrying the lamp bulb and mounted to move in and out and located in the part of the handle adjacent the casing.

5. In a reflecting lamp, the combination with a light transmitting cover; of a reflector carrying casing at the front of which said cover is disposed; a hollow handle; a bracket for supporting the lamp and which is clamped by the handle to the casing; a lamp bulb; and a shell carrying the lamp bulb and located in the part of the handle adjacent the casing, the part of the handle containing the shell being reduced to form a neck in which the shell is received.

6. In a reflecting lamp, the combination with a light transmitting cover; of a reflector carrying casing at the front of which said cover is disposed; a hollow handle formed separately from the casing; a bracket for supporting the lamp, the handle clamping the bracket and casing together; a lamp bulb; and a shell carrying the lamp bulb and located in the part of the handle adjacent the casing, the part of the handle containing the shell being reduced to form a neck in which the shell is received.

7. In a reflecting lamp, the combination with a light transmitting cover; of a reflector carrying casing at the front of which said cover is disposed; a hollow handle; a bracket for supporting the lamp and which is clamped by the handle to the casing; a lamp bulb; and a shell carrying the lamp bulb and mounted to move in and out and located in the part of the handle adjacent the casing, the part of the handle containing the shell being reduced to form a neck in which the shell is received.

8. In a reflecting lamp, the combination with a light transmitting cover; of a reflector carrying casing at the front of which said cover is disposed; a hollow handle formed separately from the casing; a bracket for supporting the lamp, the handle clamping the bracket and casing together; a lamp bulb; and a shell carrying the lamp bulb and mounted to move in and out and located in the part of the handle adjacent the casing, the part of the handle containing the shell being reduced to form a neck in which the shell is received.

In witness whereof, I hereunto subscribe my name this 31st day of January A. D. 1917.

HARRY A. DOUGLAS.
